UNITED STATES PATENT OFFICE.

WILHELM REINERS AND GUSTAV KAHLISCH, OF MUNICH-GLADBACH, GERMANY.

ROTARY THREAD GUIDE FOR CROSS-WINDING FRAMES.

Application filed May 28, 1924. Serial No. 716,385.

To all whom it may concern:

Be it known that we, WILHELM REINERS, manufacturer, and GUSTAV KAHLISCH, engineer, subjects of the German Republic, residing at Munich-Gladbach, Germany, Rheydterstrasse 48 and Westrasse 4, have invented certain new and useful Improvements in Rotary Thread Guides for Cross-Winding Frames, of which the following is 10 a specification.

In winding frames, rotary thread guides formed of wire or sheet metal wings instead of traversing thread guides or split drums have been previously used, as evidenced by 15 the German patent record No. 231,800. In a rotary guide of this kind, two wings are shaped and arranged so as to provide peripheral guiding edges which are supported on radial arms pointing vertically towards 20 the axis of the rotary guide, the radial arms of each wing being fastened to two collars in such a way that each collar supports one arm of each wing. In this arrangement, the radial arms supporting the ends of the guiding edges are in the way of the yarn which 25 therefore cuts grooves into them:—these grooves catch and break the yarn and cause it to be wrapped round the centre of the rotary guide, causing great loss of time and 30 considerable loss of material as waste. In this known type of rotary guide, the free and easy passage of the yarn also requires sufficient space to be left between the radial wing arms in each collar, to ensure that the 35 yarn slips easily from one wing to the other. Owing to these great difficulties, the aforementioned rotary guide has been found to be applicable only to pirln winding frames, but not to cross winding frames. In the 40 case of cross wound spools or cheeses, the yarn requires to be more efficiently controlled whilst winding, particularly at the reversing points, where the yarn must be guided in such a positive fashion that all 45 the layers of yarn on the cheese will have the same width so as to ensure cheeses with straight edges. Such control is also obtainable by means of the ordinary split drum, but the latter has great drawbacks, 50 as for instance the excessive weight of the revolving masses, fly collecting inside the drum and periodically settling on the yarn being wound as the fly is not easily removed, the difficult access to the inside of the split

drum causing loss of time when removing a 55 broken end which has been wrapped round the shaft of the split drum. Whilst these drawbacks are absent in the above-mentioned rotary wing guide, we have seen that the latter cannot guide the yarn sufficiently 60 well, for use in cross winding frames, particularly at the points of reversal, the more so as the control by the wings does not extend over the whole circumference of the rotary guide, seeing that the circumference 65 of the wing guide, as viewed in the direction of the shaft, does not form a complete circle, but a circle which is interrupted in two places. Whilst there is a type of rotary 70 thread guide which obviates this drawback by being composed of two rings forming a slot between them, this guide has the drawback that both rings extend over the whole circumference and are therefore necessarily 75 heavier,—moreover, the narrow slot controlling the thread everywhere on both sides imposes a greater strain on it and causes more fly which cannot drop out of the closed rings so freely,—besides, the yarn requires 80 to be threaded into the slot by hand, as in the case of the split drum, which renders the attendance considerably more troublesome.

The present invention has for its object 85 the reduction of all these drawbacks by placing the inner arms of each wing in a sufficiently slanting position with regard to the axis to get them out of the way of the yarn being guided by the peripheral guiding edges. At the same time, these two inner 90 arms are shaped in such a way that they serve as lead-over guides to pass the yarn automatically from one wing to the other, the perfect control of the yarn being thus always maintained by either one or the other of the wings. In some cases it is sufficient to place the inner arms on the slant only to a limited extent, so as to put the yarn under rather less tension than in 95 the case of the wing guides with radial arms only, whilst in other cases it is desirable to take the inner arms so far out of the way of the yarn that the latter will not touch them at all. The peripheral parts of the two 100 wings of the rotary guide forming the object of this invention are extended in the direction of their circumference so far that the side view of the guide shows a closed 105

circle, whilst the inner arms of the wings are developed in such a way that together with a part of the guide edges of the wings they form a threading device for the yarn.

5 The wings themselves may be of any cross section desired, they may be made of wire or of sheet metal, in the latter case for instance by taking an ordinary split drum and cutting-away all the material save that necessary to leave the desired guiding edges, doing away with all unnecessary weight, allowing the yarn to drop automatically into the revolving guide, and preventing fly from settling inside the rotating body of the guide. The arms which take-over the yarn from one wing to the other, will in this case be formed by corresponding metal strips which are left standing from the two halves of the split drum. The body of the wings 10 remains connected to the bosses of the former split drum by what must be left standing of the ends of the latter. It is also feasible to develop the two guide wings as metal plate segments, the edges of which must 15 have the same characteristic shape as described above for the wire wings, whilst the parts corresponding to the slanting wire arms must also be kept out of the way of the yarn substantially as described above for 20 the wire guide. The guide edges must be rounded and smoothed. The body of the segments may be perforated or partly taken-away, or its weight may be reduced in other suitable ways.

25 The boss carrying the two wings of the rotary guide may be in one piece or in several parts in such a way that each wing is carried on a separate collar. In the latter case, the two collars of the pair of wings 30 may be fastened on a boss common to both collars, and this boss may be arranged on a shaft, from which it is driven by friction in some suitable fashion.

In order to afford protection to the person attending to the machine, and particularly to do away with the feeling of the danger of accidents to her which would interfere with the proper attention to the machine, protection appliances may be used, 35 such as detachable or hinged protection plates or the like, which may be slotted for the purpose of the automatic introduction of the yarn into the revolving wing guide. In those cases where such protection appliances not used, means for the certain and automatic introduction of the yarn into the wing guide may be provided by having a thread guide of wire or the like of suitable shape to ensure the proper guiding of the 40 yarn into the revolving wing guide.

Obviously it is impossible to drive the bobbin itself by friction from a wing guide as described. In cross winding frames having a revolving wing guide of the type hitherto known and as mentioned in the in-

trodition, it is possible to use a driving drum arranged laterally for driving the cheese, but in such an arrangement the guiding of the yarn by the rotary guide of the old type was absolutely insufficient for the 70 reasons which have already been stated. There are also cross winding frames with split drum having an intermediate roller of small diameter which serves as a guide to the yarn and which receives motion by friction from the surface of the split drum, transmitting same again by friction to the cheese, but in this case friction losses cannot be avoided and as a consequence the bobbin is irregularly wound. In order to ensure in our present invention proper guiding of the yarn from the point where it leaves the revolving wing guide up to the point where it is placed on the spool, such a little roller driving the bobbin is placed between 85 the flyer thread guide and the spool, but whilst this roller of small diameter is in itself known, we ensure regular winding of the spool or cheese by introducing a positive driving connection between the shaft 90 of the rotary wing guide and the roller of the small diameter which also serves as thread guide.

The drawings represent the following details:

Figures 1 and 2 show a part of the cross winding frame fitted with the object of the invention, in front and side view respectively.

Figures 3, 4 and 5 show an example of the 100 revolving flyer guide as made of wire, in 3 views.

Figures 6, 7 and 8 show the revolving flyer guide as obtained from cutting certain parts away from the pair of halves of 105 a split drum, in three views.

Figure 9 shows a revolving wing guide according to the invention as made of two metal plates which are suitably curved and shaped and unessential parts of which may 110 be cut away so as to render it lighter.

Figs. 10 to 13 show a pair of revolving wing guides as cast or stamped out of metal, Figs. 10 and 11 showing the two wing parts separately, whilst the pair is shown on its 115 shaft in Fig. 12, Fig. 13 showing a top view of the arrangement represented by Fig. 12.

In the example as represented by Figs. 1 to 5, each wing guide consists of a circular wire part 16 extending from 12 to 13 and 120 a similar part 17 extending from 14 to 15 running in the direction of the arrow marked α and supported on arms a , b , c made of the same wire for the purpose of fixing the guides on the collars 18 and 19. 125 Both collars are fastened on a common boss 20 which is loose on the thread guide shaft 21 but driven by the latter by friction in some suitable way, say by a kind of friction coupling, as mentioned already. This fric- 130

tional connection is intended to allow an immediate stoppage of the thread guide in case the attendant gets her hands into the wing guides, that is to prevent accidents.

5 Instead of providing such a coupling for each separate thread guide, it can also be applied to groups of guides. When seen from the side, the annular parts 16 and 17 form a closed circle, the more so as the two 10 fractional parts of a circle cover each other between 12 and 15 and between 13 and 14, in such a way as to form at these points slots *d*, as clearly shown in Fig. 5. The point of reversal of the yarn is at 13 for the 15 arc 17, and at 15 for the arc 16.

The three parts 18, 19 and 20 can be made of one piece if the relative adjustment of the two guide wings with regard to one another is not necessary.

20 Figure 2 shows only part of the machine and only two yarn guides and it shows also the small diameter roller 26 between the revolving thread guides and the bobbins. This small roller 26 may be driven by band 25 27 from the same axis which drives the shaft of the rotary wing guide. The bobbins may be carried in frames 28 in the usual well known fashion and rest on the shaft 26 which may be of the length of the complete 30 machine, in which case it would drive all the cheeses on one side of the frame at the same time, but this roller may also be arranged so as to drive every spool separately or drive groups of bobbins. As will be seen 35 from Figures 1 and 2, the roller 26 serves also as a guide for the yarn after the latter has left the revolving wing guide, the yarn running over part of its circumference in such a way that it will always assume the same 40 position on the roller every time it passes the position of reversal in consequence of its tension and of the friction on the roller, thus ensuring that the width of traverse of the yarn on the spool is always the same 45 and that therefore the ends of the cheese are straight and faultless.

As shown in Fig. 1, the machine can be fitted with hand rests 29 along the whole frame, in order to facilitate the piecing 50 operation on the part of the attendant. Protection plates 30 are also shown hinged at a rod 31. Between the protection plates which are shown in dotted lines only, there are slots 32 for the yarn to pass through and 55 which serve at the same time to introduce the yarn automatically into the revolving wing guides. Where protection plates are not wanted and where therefore only a device for the secure introduction of the yarn into the revolving wing guide is required, such device may take some other form of wire, metal plate, or the like, and it may be 60 applied separately.

In the example as per Figs. 6 to 8, certain parts have been cut away from a pair

of ordinary split drum halves, the parts left representing only the actual guiding edges and their necessary support, whilst the parts which are not essential for the guiding of the yarn have been eliminated, thus incidentally allowing the yarn to thread itself automatically into the revolving wing guide and preventing fly from settling inside the guide. For the purpose of easy comparison, the various parts are marked with the same reference characters, primed as shown in Figs. 3 to 5. The arms *a'* are formed partly by the drum shell, partly by the end faces of the drums or by parts of same. Fig. 9 shows the rotary wing guide as made of two segment discs 16'' and 17''. In each of the cases represented by Figs. 6 to 9, the little roller 26 is also essential, because without same the spools cannot be properly driven and the yarn cannot be laid on the 85 spool with the required exactitude the more so as the least lateral deflection of peripheral parts of the guide wings is bound to give rise to irregularities.

In the working example as per Figures 10 to 13, the parts 16''' and 17''' are the peripheral guiding parts, *a'''* and *b'''* the guiding arms, whilst *c'''* represents strengthening stays. Those parts of the periphery and of the arms which serve as guides to the yarn must also in this case be shaped in accordance with the requirements outlined above. The way of manufacture of the segment discs whether by stamping, casting, or in other suitable ways, does not form part of the subject matter of the invention, seeing that the separate segment discs are made of one piece with their corresponding collar soldering and squaring operations are unnecessary, thus saving time and considerably reducing the cost of manufacture of the guide wings. In cases where the guide wings are made of a light metal, the centrifugal action on the peripheral parts may be reduced, thus causing a corresponding reduction of the weight and strain on the shaft carrying the rotary wing guides, with the possibility of reduction of the diameter of this shaft.

Claims:

1. A rotary thread guide for cross winding frames, comprising rotating wings having their peripheral guide elements angularly disposed relative to their axis of rotation, and supporting arms for said guide elements, the supporting arms for the trailing ends of said guide elements being sloped away from the respective trans-axial planes of said guide elements, as described.

2. A rotary thread guide for cross winding frames, comprising rotating wings having their peripheral guide elements angularly disposed relative to their axis of rotation, and supporting arms for said guide elements, the supporting arms for the trailing ends of said guide elements being sloped away from

- the respective trans-axial planes of said guide elements for preventing contact of the thread with said arms, as described.
3. A rotary thread guide for cross winding frames, comprising rotating wings having their peripheral guide elements angularly disposed relative to their axis of rotation, and supporting arms for said guide elements, the supporting arms for the trailing ends of said guide elements being sloped away from the respective trans-axial planes of said guide elements for guiding the thread in its passage to the succeeding guide element, as described.
- 15 4. A rotary thread guide for cross winding frames, comprising rotating wings having their peripheral guide elements angularly disposed relative to their axis of rotation, and supporting arms for said guide elements, the supporting arms for the trailing ends of said guide elements being sloped away from the respective trans-axial planes of said guide elements, said guide elements overlapping each other, as described.
- 25 5. A rotary thread guide according to claim 1 in which the peripheral part of each wing is made of one piece with the arm and collar parts, the unessential parts of the wings being eliminated.
- 30 6. Rotary thread guide according to claim 1 in which the peripheral parts of each wing
- is made of one metal strip in one piece with the corresponding arms.
7. A rotary thread guide according to claim 1, in which each wing is supported on a separate axial collar.
8. In combination with a rotary thread guide according to claim 1, one or more protection plates arranged in front of the revolving wings, said protection plates having slots for admitting the yarn.
9. In combination with a rotary thread guide according to claim 1, a pair of protection plates disposed adjacent each guide whereby the introduction slot for the yarn is formed by a space between each pair of said protection plates.
10. In combination with a rotary thread guide according to claim 1, a separate yarn introduction device operatively disposed relative to said guide.
11. In combination with a rotary thread guide according to claim 1, a driving roller for the cheese, said roller being driven in conjunction with said rotary thread guide and serving as a guide for the thread between the rotary thread guide and the cheese.

The foregoing specification signed at Cologne, Germany, this 13th day of May, 1924.

WILHELM REINERS.
GUSTAV KAHLISCH.
